CEDAR CHEST

John Weber, Milton, Pa., assignor to West Branch Novelty Company, Milton, Pa.

Application February 21, 1934, Serial No. 712,409

4 Claims. (Cl. 217—56)

This invention relates to cedar chests and more particularly to a new and novel construction of dust strip whereby an air cushioning effect is produced by the sudden closing of the lid and objectionable slamming of the lid upon the chest is avoided.

It is also an object of the invention to provide a dust strip adapted to cooperate with the walls of the chest in such a way as to take advantage of certain irregularities of contour which are present in the most carefully constructed chests, thereby to further assist in preventing the lid from slamming.

No matter how carefully a cedar chest may be constructed certain irregularities of contour will be present in the upper edges of the walls on completion or will occur as a result of atmospheric conditions following the completion of the chest. Where a channeled dust strip is used it is practically impossible to so place the strip as to accurately match the walls under all conditions. Dust strips having channels have been used but in every case they have been made with channels of excessive widths in order to allow for the variations referred to and, in order to effect the desirable sealing of the chest or produce a tight fit between the parts it has been the practice generally to use cushioning elements of metal, rubber or the like. Aside from the fact that these have added greatly to the cost of the chest, these cushioning means, if made of metals, have also been objectionable because they tend to accumulate a gummy residue deposited by the cedar fumes within the chest and which, if brought into contact with garments, will stain them and be difficult to remove. Furthermore where channels of excessive widths are used a desirable cushioning effect by the trapped air within the chest is prevented because the air can escape too freely when the lid is closed.

It is an object of the present invention to provide the lid of a cedar chest with a dust strip having a channel the walls of which converge upwardly, the narrowest space between these walls being but slightly greater than the thickness of the walls of the chest. Thus when the lid is dropped to closed position the air in the path thereof will be trapped not only within the chest but also within the channel. It can escape solely laterally and forwardly from under the lid and, as the channeled dust strip gradually moves into position to straddle the walls throughout the length of the channel, the air will be further trapped and can escape solely by following a tortuous path over the walls. This path

is gradually reduced as the inclined walls of the channel come closer to the top edges of the walls. This choking action increases the cushioning effect to a considerable extent and has greatly reduced the slamming action of lids not provided with dust strips similarly constructed.

It is a further object to provide the channel in the dust strip with inclined walls so that any portion of either wall can act as a deflector and retarding means should it come into contact with any part of the wall not properly matched with the dust strip, thereby serving as a further means for resisting the slamming of the lid when dropped onto the chest.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a side elevation of a portion of a chest showing its lid partly raised.

Figure 2 is a bottom plan view of the lid, a portion being broken away.

Figure 3 is a transverse section through portions of the lid and chest showing the relative positions of the chest walls and dust strip at one point during the closing of the lid.

Figure 4 is a view through a portion of one of the walls and the adjacent part of the lid showing the action of the dust strip as a retarding means where the wall and dust strip are not accurately matched.

Figure 5 is a view similar to Figure 4 showing the positions of the parts when the lid is finally seated on the chest.

Referring to the figures by characters of reference 1 designates a cedar chest having hinges 2 for joining it to a lid 3. To the bottom of the lid along the edge portions thereof is secured a dust strip 4 having a continuous channel 5 the inner wall of which is of a width substantially equal to or slightly greater than the thickness of the top edges 6 of the chest walls 7. The inner and outer walls 8 of the channel 5 converge toward the inner wall of the channel as shown and either of these walls can act as a deflector should it come into rubbing contact with any part of the chest while the lid is being closed.

As has already been stated it is practically impossible, in a cedar chest, to provide a grooved dust strip on the lid which will accurately match the walls of the chest under all conditions. Consequently, where channeled dust strips have been used the channels have been made of excessive widths and this has been objectionable because the chest has not been properly sealed against the admission of dust or the escape of fumes.

10 Furthermore the dust strip has not had any function as an air trapping medium or as a cushioning element.

For the purpose of improving upon structures thus far produced the present devices has been evolved after long experimental use. It has been discovered that by providing a channel which is tapered substantially as shown a correct sealing action is not only obtained between the lid and the walls of the chest but a double cushioning effect is produced should the lid be dropped to closed position. One cushioning effect results from the trapping of air while the other results from the wiping action of one or more of the walls of the dust strip upon those portions of the walls of the chest which do not properly match with the channel.

When the lid is dropped the air thereunder seeks to escape past the edges of the lid. This escape will be retarded where the walls are first straddled by the dust strip and as the lid continues to move downwardly the escape of the air will be increasingly retarded by the increased area of the straddled portions of the walls until ultimately all of the walls will be straddled throughout their lengths. When the air seeks to escape past the straddled portions of the walls it must of necessity follow a tortuous path up into the channel, over the wall and thence downwardly and outwardly from the channel. The freedom of flow in this manner is gradually reduced by the movement of the tapered walls toward the adjacent edges of the chest walls. Thus the air under the lid is gradually trapped or confined and at the same time air within the channel is forced in part longitudinally of the channel, thereby producing a cushion which, in conjunction with the air trapped under the lid and within the chest, will prevent the abrupt slamming which otherwise would occur. As the dust strip moves into position astride the walls of the chest some part of one or more of the inclined walls of the channel will come against one or more of the edges of the top surfaces of the chest walls with the result that wiping action will occur between these contact parts and effect a gradual frictional retard which further serves to prevent slamming.

When the lid is brought ultimately to its closed position the walls of the chest will be fitted snugly against the inner walls of the channel with the inclined walls of said channel extending close thereto and effecting an efficient seal.

What is claimed is:

1. The combination with a cedar chest, of a lid hingedly connected thereto, and a dust strip upon the bottom of the lid and of the same material as the lid, said strip having a channel the side walls of which converge upwardly to the inner wall of the channel, said inner wall being of a width substantially equal to the thickness of the chest walls and constituting a seat therefor, the upwardly converging side walls of the channel being disposed at such a pitch as to retard the escape of air from between the walls of the channel and the walls of the chest during the abrupt closing of the lid.

2. The combination with a cedar chest, of an all-wood sealing and cushioning means therefor including a lid hingedly connected thereto, a dust strip on the lid having a continuous channel for receiving the upper edges of the walls of the chest, the walls of the channel converging toward the inner wall thereof and constituting means for effecting a wiping contact with any portions of the walls of the chest not accurately matched with the inner wall of the channel, the minimum distance between the walls of the channel being substantially equal to the thickness of the walls entering the channel, the upwardly converging side walls of the channel being disposed at such a pitch as to retard the escape of air from between the walls of the channel and the walls of the chest during the abrupt closing of the lid.

3. The combination with a cedar chest, of a wooden lid hingedly connected thereto and combined sealing and cushioning means carried by and of the same material as the lid, said means including a dust strip having a continuous channel for receiving the upper edges of the walls of the chest, the sides of the channel converging toward the inner wall thereof and constituting means for effecting a wiping contact with any portions of the walls of the chest not accurately matched with the inner wall of the channel, the upwardly converging side walls of the channel being disposed at such a pitch as to retard the escape of air from between the walls of the channel and the walls of the chest during the abrupt closing of the lid, the width of the inner wall of the channel being substantially equal to the width of the top edges of the chest walls contacted thereby.

4. The combination with a cedar chest, of a wooden lid hingedly connected thereto and having a continuous channel for receiving the upper edges of the walls of the chest when the lid is closed, the top wall of the channel being of substantially the same width as the upper edges of the chest walls, the walls of the channel converging upwardly and being disposed at such a pitch as to retard the downward escape of air from between the lid and chest walls, thereby to provide an air cushion between said walls and the lid during the rapid closing of the lid.

JOHN WEBER.
